UNITED STATES PATENT OFFICE.

FRANK CHATEAUNEUF, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

TURN-SHOE SOLE.

1,216,073.

Specification of Letters Patent. Patented Feb. 13, 1917.

Original application filed May 26, 1913, Serial No. 769,879. Divided and this application filed July 25, 1914. Serial No. 853,156.

To all whom it may concern:

Be it known that I, FRANK CHATEAUNEUF, a citizen of the United States, residing at Swampscott, in the county of Essex and State of Massachusetts, have invented certain new and useful Improvements in Turn-Shoe Soles; and I do hereby declare the following to be a full, clear, and exact description of the invention, such as will enable others skilled in the art to which it appertains to make and use the same:

The present invention relates to shoe soles and more particularly to soles for turn shoes.

This application is a division of my co-pending application Serial No. 769,879, filed May 26, 1913.

The object of the invention is to improve the construction of turn shoe soles particularly with respect to the shoulder and feather cut in the marginal portion of the sole. With this object in view the present invention consists of the shoe sole hereinafter described and particularly pointed out in the claims.

25 In the drawings which illustrate the preferred embodiment of the invention Figure 1 is a perspective view of the sole and Figs. 2 and 3 are sections taken along the lines 2-2 and 3-3 respectively of Fig. 1.

30 In the drawings the invention is illustrated as embodied in a turn shoe sole 1 which has been shouldered and channeled, as for example by means of the machine disclosed in my co-pending application Serial

35 No. 769,879 above referred to. The channel 200 is cut in the flesh side of the sole 1 and opens inwardly or toward the middle of the sole to receive the line of stitches which pass through the between-substance and unite the 40 sole and upper in the completed shoe. Joined to the between-substance and lying above the channel is the usual channel flap 201. On the outer side of the between-substance is cut the outwardly facing shoulder 202 against which the upper is sewed. This shoulder is under-cut at its base with a round bottom groove 203 opposite the bottom of the channel 200, leaving an overhanging tongue 204 at the top of the shoulder. Before the upper

45 is sewed to the sole, the feather 206, which extends outwardly beyond the tongue 204 to form the margin of the sole, is bent toward the grain side of the sole by means of a sole edge molding machine, so that the groove 203

is spread open to receive the inseam stitching. The shoe upper and the two-thread side of the chain stitch, which is generally used for the inseam, are drawn into the groove 203 by the setting of the stitches. After the upper is sewed to the sole and the inseam 55 trimmed and the shoe turned and beaten out, the tongue 204 extends out over the inseam-receiving groove 203, and the inside of the shoe sole is much smoother over the inseam than would be the case if the shoulder were 60 not under-cut. The outer edge or face of the tongue 204 is straight. This straight face on the end of the tongue 204 prevents a ragged or irregular tongue edge. The upper face of the feather 206 is flat or straight and is inclined 65 to the plane of the sole. Along the forepart of the sole, the upper face of the feather 206 extends outwardly in a direction inclined upwardly or away from the grain side of the sole so that the edge or margin of the sole is 70 approximately as thick as the sole. Along the shank of the sole, the upper face of the feather 206 extends outwardly in a direction inclined 75 downwardly or toward the grain side of the sole so that the edge or margin of the feather is beveled to a thin edge. The sole therefore has the comparatively thick edge along the forepart and the beveled edge along the shank which conduce to an attractive appearance in the finished shoe.

80 The present invention is not limited to its preferred embodiment but may be embodied in other shoe soles within the scope of the invention as set forth in the following claims.

I claim:

1. A turn shoe sole having an inwardly-opening stitch-receiving channel cut in the flesh side of the sole, a channel flap, an outwardly facing shoulder cut in the flesh side of the sole and having at its base an undercut groove opposite the bottom of the channel for receiving the inseam, the upper part of the shoulder forming a tongue overhanging the groove, when the channel flap lies adjacent the part of the sole from which it was cut, and a feather forming the margin of the sole having its upper face flat and extending outwardly from the base of the shoulder in a direction inclined to the plane of the sole.

2. A turn shoe sole having an inwardly-opening, stitch-receiving channel cut in the flesh side of the sole, a channel flap, an out-

- wardly facing shoulder against which the upper is sewed cut in the flesh side of the sole and having an undercut base opposite the bottom of the channel when the channel flap lies adjacent the part of the sole from which it was cut, and a feather forming the margin of the sole having its upper face extending outwardly from the undercut base of the shoulder in a direction inclined to the plane of the sole.
3. A turn shoe sole having an inwardly-opening, stitch-receiving channel cut in the flesh side of the sole, an outwardly facing shoulder against which the upper is sewed cut in the flesh side of the sole and having an undercut base opposite the bottom of the channel, and a feather forming the margin of the sole having its upper face extending outwardly from the undercut base of the shoulder in a direction inclined away from the grain side of the sole to form a thick edge or margin on the sole.
4. A turn shoe sole having an inwardly-opening, stitch-receiving channel, an outwardly facing shoulder against which the upper is sewed cut in the flesh side of the sole and having an undercut base opposite the bottom of the channel, and a feather forming the margin of the sole having its upper face extending outwardly from the undercut base of the shoulder in a direction inclined away from the grain side of the sole along the fore part and in a direction inclined toward the grain side of the sole along the shank to form a thick edge or margin along the fore part and a thin beveled edge or margin along the shank.
5. A turn shoe sole having an inwardly-

opening stitch-receiving channel cut in the flesh side of the sole, an outwardly-facing shoulder against which the upper is sewed cut in the flesh side of the sole and having a stitch-receiving groove formed at its base by cutting into the leather opposite the bottom of the channel, and a feather extending beyond the shoulder to form the margin of the sole, the upper surface of said feather being inclined in one direction along a part of the sole, and being inclined in another direction along another part of the sole.

6. A turn shoe sole having an inwardly-opening stitch-receiving channel cut in the flesh side of the sole, a channel flap, an outwardly extending tongue having a straight outwardly-facing face, a feather forming the margin of the sole and having a straight upper face inclined to the plane of the sole, and a groove, at the angle between said straight faces, when the channel flap lies adjacent the part of the sole from which it was cut, formed by cutting inwardly into the leather opposite the bottom of the channel.

7. A turn shoe sole having an inwardly-opening stitch-receiving channel cut in the flesh side of the sole, an outwardly extending tongue having a straight outwardly-facing face, a feather forming the margin of the sole, and a groove at the angle between the faces of the tongue and feather formed by cutting inwardly into the leather opposite the bottom of the channel.
